UNITED STATES PATENT OFFICE

HENRY BELIN, 3D, OF SCRANTON, PENNSYLVANIA, ASSIGNOR TO THE SCRANTON LACE COMPANY, OF SCRANTON, PENNSYLVANIA, A CORPORATION OF PENNSYLVANIA

LACE

Application filed February 6, 1932. Serial No. 591,329.

This invention relates to laces and particularly to machine made laces which have colored patterns or spots differing in color from the color of the back-ground or foundation of the lace.

Among the objects of my invention is to produce lace having the appearance of uniformity in weight throughout its back-ground, even though the lace has pattern spots of colored threads which do not extend any substantial degree beyond the pattern spots and into the back-ground of the lace.

Another object of the invention is to provide novel methods of making lace and laces which are durable and attractive notwithstanding that a portion of the spool threads which are used in their manufacture are subsequently clipped and removed from between pattern spots. Heretofore laces containing threads of different colors have been made by various methods, most of which entail much expense or are productive of a lace lacking in quality and saleability. Colored lace may be made by the common methods of making lace on Nottingham lace curtain machines, but the principal objection to such lace lies in the fact that the colored spool threads which produce the colored pattern spots impart to the background or foundation of the lace a colored striped appearance caused by the pil-lared spool threads between successive pattern spots. This objectionable feature has been overcome by causing the spool thread to be floated from one pattern spot to another, thereby leaving loosely hanging lengths of colored thread intermediate successive pattern spots which may be readily clipped and removed from the lace. However, this removal of the objection to a colored stripe appearance is not altogether satisfactory because in place of the stripe possessing a colored cast there results a stripe caused from the lack of balance or uniformity in the apparent weight of the back-ground or foundation of the lace. This is due to the fact that

the uniformity of lace made on a Nottingham lace curtain machine, such as filet, is dependent upon all of the threads which are used in producing the lace and when any of the threads are removed, such as occurs when 50 spool threads are floated and clipped, there results a lightness in weight of the lace in the areas or spots wherein the spool threads would have been woven if they had not been floated and removed. For example, in filet 55 lace made according to this method, in the lace structure between the longitudinal strips containing the pattern spots, the spool threads are pillared to the warp threads and these areas are of normal weight, but in the longitudinal strips containing the pattern spots the back-ground of the lace between successive pattern spots lacks the spool 60 threads and therefore the lace is weaker in these areas as well as objectionable because 65 of a striped effect.

The objections related are serious enough to curtail the saleability of a lace made in this manner and it is among the objects of my invention to overcome these objections and 70 produce lace which is balanced and substantially uniform in weight throughout its surface. The manner by which I have accomplished this will be apparent from the following description and drawings, in 75 which:

Fig. 1 is a diagrammatic representation of a fabric made in accordance with the method of my invention.

Fig. 2 is a pattern draft for the fabric 80 illustrated in Fig. 1.

Fig. 3 is a pattern draft showing the application of my invention to another lace design.

Fig. 4 is another pattern draft similar to 85 that illustrated in Fig. 3, but showing another feature of my invention.

While it will be apparent hereinafter how the method of the present invention may be practiced for the manufacture of different 90

laces, including laces requiring, an extra bar for their manufacture, such as filet madras, straight madras, dubonnet, bar-ground and cross ground, for the purpose of simplifying this disclosure, I have chosen to illustrate its application to a simple form of filet lace of which a diagrammatic showing is reproduced in Fig. 1. In general, lace which is made on Nottingham lace curtain machines is made up of a plurality of warp threads which form the backbone of the lace, and three other threads—the spool, the beam and the bobbin. The spool thread throws in the pattern and is pillared upon the warp thread between pattern spots. The beam thread makes the back-ground and the bobbin thread twists around the spool and beam threads and ties them to the warp threads. In a simple form of filet lace having no pattern spots, the lace has the appearance of net with square meshes and in such a lace the spool threads are everywhere pillared to the warp threads. The appearance of a plain net of this character is uniform throughout. When a pattern is to be made on filet lace, the jacquard cards are punched in such a manner as to cause the spool threads to be thrown to make patterned spots or pillared to the warp threads to produce the pattern for which the jacquard cards have been punched.

Having reference to Fig. 1 in which I have shown a diagrammatic reproduction of a filet lace made in accordance with my invention, 10 designates the area in the back-ground in which the spool threads are pillared to the warp threads. These areas run in longitudinal strips between 10a and 10b and between 10c and 10d. The warp threads 11 run vertically or longitudinally of the fabric. The spool threads 12 within the longitudinal strips 10 are pillared or tied to the warp threads 11. The threads which run parallel to the warp threads and transverse thereto alternately are the beam threads 13, and the threads which twist about the warp threads and tie in the remaining threads are the bobbin threads 14. The spool threads which form the pattern spots composing the decorative figures or objects are identified as 15. The warp, beam and bobbin threads perform the same function throughout the entire area of the portion of the lace illustrated. For convenience I shall refer to the back-ground or foundation as being that portion of the lace which is exclusive of the thread which forms the pattern spots composing the figures 15 and 16.

While my invention has its greatest application to laces in which the colors of the figures contrast with or differ from the color of the back-ground I wish it to be understood that its various features are useful irrespective of the presence of color or of the manner in which colored threads are used. For the

purpose of the present disclosure, it will suffice, however, to describe the invention by reference to the use of a single color for producing pattern spots and a solid color back-ground, for example, pattern spots produced by green threads on a white back-ground. Since the back-ground of this particular lace is to be made in solid color, all of the four threads which are used for producing the back-ground are of one color, in the present instance, white. The figures which are to be green, are produced by a green spool thread, but the remaining three threads which are present in the longitudinal strip containing the figures are of the same color as the back-ground of the lace, in the present example, white. In producing the lace illustrated in Fig. 1, the spool threads 12 between 10a and 10b and between 10c and 10d are white, and the spool threads 15 between 10b and 10c are green. As is well understood, the green spool threads 15 are floated between detached figures, and as may be seen from Fig. 1 there are no spool threads illustrated between the successive detached figures 16, 17.

The patterned spots which compose a figure may consist of a single square 18 or a number of contiguous squares 19 which are produced by throwing the spool thread. As is well known in the art, this operation is controlled by the guide bars under the control of jacquard cards. If the green spool threads had not been floated between successive figures 16, 17, the lace would have a green cast because of the pillaring of the green threads between the two figures. However, the floating and clipping of spool threads between successive figures results in a strip containing the pattern spots which has the appearance of being lighter in weight than the adjacent longitudinal strips or areas 10 which do not contain figures composed of pattern spots. In addition to being of light weight, the areas between successive figures would be of less strength than the fabric in the adjacent longitudinal strips 10 in which none of the threads used in making the lace has been removed. In order to overcome these disadvantages I have produced the lace of my present invention by using warp threads between 10b and 10c which are of greater weight than the warp threads in the longitudinal strips 10. The weight for these heavier warp threads should be such as to counterbalance the loss in weight because of the clipping of the spool threads from between successive figures so as to produce a fabric having the appearance of uniformity of weight throughout its back-ground.

As may be seen in Fig. 1, the relative weights of the warp threads are indicated by the difference in the weight of the lines representing the threads. Because of the differ-

ence in weights of the warp threads used in making a length of lace, it is not possible to use a common beam from which all of the warp threads may be drawn as the lace is fabricated. It is therefore necessary to equip the lace-making machine in such a manner as to enable the mounting of separate spools carrying warp threads, and for this purpose I have found it convenient to equip the machine with a large spool board at the back, and for practical purposes prefer this arrangement. Spools are placed on the board containing warp threads and this arrangement permits the use of warp threads of any size desired because of the independent relation of the spools carrying warp threads of different weights. With such an arrangement, lace may be obtained which is absolutely even and clear.

In Fig. 2 I have illustrated a pattern draft from which the jacquard cards for producing the fabric illustrated in Fig. 1 may be punched. In this figure conventional coloring has been used to imitate the appearance of an actual pattern draft. It is the usual practice to paint the draft with colors for indicating the manner in which the jacquard cards should be punched to produce a certain pattern. For example, the areas within which all spool threads are floated are painted in one color, say green, all colored pattern spots within a figure are painted in another color, say blue, all pillared colored threads are painted in another color, say orange, all white pattern spots within a figure are painted in another color, say red, and for all pillared white threads the paper is left white. To punch the pattern on jacquard cards, card No. 1 is punched to put in the pattern parts, that is, those parts painted blue and those parts painted red. Card No. 2 is punched to put on the pattern parts, that is, those parts painted blue and those parts painted red; the pillared threads or those parts which have not been painted and are white; and the pillared colored threads, or those parts painted orange. The jacquard cards are then used on the lace machine in conjunction with the guide bars and in a way that is well-known by those familiar with the operation of lace-making machines.

Having reference to Fig. 2, and having in mind the color code set forth hereinabove, one may readily understand how the lace illustrated in Fig. 1 may be produced. Within the areas shown as blue, such as 116 and 117, the colored spool threads are thrown to fill in the pattern spots. Within the area conventionally shown as green, the spool threads are floated. The orange coloring indicates parts such as at 120, wherein the colored spool threads are pillared. In the fabric a hole, such as shown at 20, Fig. 1, is produced by pillaring the colored spool thread between pattern spots with the result

that the colored spool thread does not show between adjacent pattern spots, as would be the case if the spool threads were floated.

By pillaring the colored spool threads between pattern spots such as 118 and 119 and where shown in orange in Fig. 2, it is possible to produce a better-appearing and better-wearing fabric than would be the case if the colored spool threads were floated between all pattern spots. The value of this feature of my invention may be appreciated when it is applied to a more complex figure in the fabric, and I therefore illustrate in Fig. 3 a pattern draft containing detached figures in which there are several areas of contiguous meshes between pattern spots. Such areas are indicated at 21, 22, 23 and 24. The colored spool thread passing through a colored area or along its edges is pillared to a warp thread, with the result that open meshes remain.

In some cases there is no objection to the use of figures in lace in which the colored spool threads have been pillared just beyond the figures, and in order to take advantage of the strength-giving quality resulting from pillaring the spool threads and also to facilitate clipping floated spool threads, I propose the pillaring of all spool threads beyond each figure and for distances to finish pillaring in a straight line. I have represented this in Fig. 4 which shows a pattern draft of a pattern similar to that illustrated in Fig. 3, but in which the areas between lines A—A and B—B, exclusive of the figures, are marked for the pillaring of the spool threads. That is to say, the spool threads which are thrown into the patterns are conventionally indicated in blue and the colored spool threads which are pillared are conventionally indicated in orange. Another advantage of making a lace according to this method resides in the facility by which the floated spool threads between figures may be clipped. As may be readily appreciated, all of the threads within lines A—A and B—B may be clipped in one straight cutting operation. Since the figures are patterned with a colored thread, the objection is less serious to having a colored cast in the vicinity of the figure, but this method of making fabric may have greater use in such instances where the top side of the fabric may be turned under, as for example, for a table cloth. When the top side is turned under the colored cast produced by the colored threads is not in view.

In the foregoing I have endeavored to provide a full disclosure of preferred forms of my invention, and for this purpose I have shown by way of example the application of its various features to filet lace, but it is apparent that the principle involved may be applied in the production of any lace whose manufacture utilizes an extra bar, and also to Swiss or combination or Swiss and combination laces. Therefore, it is to be understood

that it is not intended to confine the invention to the embodiments herein disclosed, and that it is susceptible of embodiment in various forms and combinations, all coming within the scope of the claims which follow.

I claim:

1. As a new article of manufacture, lace made on a Nottingham lace curtain loom, said lace having figures composing pattern spots made from the thread of a color different from that of the back-ground of the lace, said pattern spots being formed by throwing colored spool thread and said figures being separated longitudinally of the warp threads by the absence of colored spool threads, and warp threads in the longitudinal strips containing figures which are heavier than the warp threads in the longitudinal strips not containing figures.
2. A substantially uniform weight lace made on a Nottingham lace curtain loom, said lace having detached figures made of colored spool threads which are discontinuous between figures in the same longitudinal strip and in which the warp threads of the lace are heavier in the longitudinal strips containing the colored figures than elsewhere in the lace to off-set the weight lost because of the absence of spool threads between adjacent figures in the longitudinal strips containing the figures.
3. A substantially uniform weight lace made on a Nottingham lace curtain loom, said lace having detached figures composed of pattern spots thrown in by spool threads which are discontinuous between figures in the same longitudinal strip and in which the warp threads of the lace are heavier in the longitudinal strips in which the spool threads are discontinuous whereby the loss in weight accountable by the absence of spool threads between figures is substantially compensated.
4. As a new article of manufacture, lace made on a Nottingham lace curtain loom, said lace having detached figures containing spool threads and no spool threads between figures in longitudinal strips containing the figures, said lace having the appearance of balance notwithstanding the absence of spool threads between adjacent figures, and wherein the appearance of balance is obtained by warp threads in the longitudinal strips containing the figures heavier than the warp threads in longitudinal strips wherein the spool threads are continuous.
5. As a new article of manufacture, lace made on a Nottingham lace curtain machine, said lace having colored patterns, objects formed by colored spool threads which have been removed from the lace between successive pattern objects in the same longitudinal strip and are pillared within the holes of the pattern objects and adjoining the end extremities of the pattern objects, and warp

threads of different weights for compensating for the lack of colored spool threads between successive pattern objects whereby the background of the lace is made uniform, the warp threads in the longitudinal strips containing the colored pattern objects being heavier than those in the longitudinal strips not containing colored pattern objects.

In testimony whereof I hereto affix my signature.

HENRY BELIN, III.
